LOG-CENTERING BARKER FEEDING MECHANISM

Rupert E. Annis, Jr., Salem, Mass., assignor to Improved Machinery, Inc., Nashua, N.H., a corporation of Maine

Application January 4, 1956, Serial No. 557,313

5 Claims. (Cl. 144—247)

This invention relates to machines for removing bark from logs, and more particularly, it relates to feeding mechanisms for such machines.

Machines to remove bark from logs are well known in the pulpwood logging industry, and often employ an angularly rotating member, or drum, carrying a number of angularly spaced knives which scrape the bark from the log as it is fed through said member. In most instances, machines of this type have proven completely satisfactory and have found wide use. Where barking operations are to be carried out on relatively short logs, however, as are commonly used for pulp in the northeastern section of the United States, considerable difficulty has been experienced primarily because of the inability of the feeding mechanism associated with the machines to handle short logs. Accordingly, there has been developed new feeding apparatus, as disclosed in application Serial No. 476,642, filed December 21, 1954, now Patent No. 2,815,776, issued Dec. 10, 1957, specially adapted for use in a debarking machine of the type therein disclosed, in that it is capable of providing firm radial support for the log and preventing the same from rotating, while at the same time advancing the log axially through the barking mechanism. It is a feature of this feeding apparatus that changes in the radial spacing of the log gripping members occur automatically in accordance with variations in the diameters of successive logs presented to the feeding apparatus.

It is an object of the present invention to provide improved feeding apparatus for a barking machine which is not only self-opening and closing, as aforementioned, but also self-adjusting in a manner whereby a firmer grip on the logs is maintained in spite of substantial differences between the diameters of successive logs and in spite of irregularities which may exist on the surfaces of some of the logs.

In brief, the feeding apparatus of the present invention is constituted by two distinct feeding mechanisms located adjacent the respective input and output ends of the barking machine, each of itself being adapted to radially restrain a log and keep it from rotating, while advancing the log axially through the drum. The feeding mechanism adjacent the input end of the barking machine supports the log in cantilever while advancing the same through the drum until it is engaged by the feeding mechanism adjacent the output end of the drum. The latter serves to continue the axial advance of the log while its trailing portion passes through the drum, and thereafter to eject the log from the machine. Each feeding mechanism has three angularly spaced endless tracks or the like disposed symmetrically about the axis of the barking machine normally both parallel and tangential to a cylinder on said axis, each of the tracks in turn being provided with a working surface including a plurality of log gripping members to engage the log during a lineal traverse of the track and thereby restrain the same against radial and rotational movement. To drive the tracks and thereby advance the log axially, there are provided

2

for each track, a pair of axially spaced sprockets carried by a pair of shafts which are so mounted that even while the track is being driven, individual pivotal movement of the tracks is allowed to take place. Thus the tracks will not only open and close to accommodate different diameters of logs but will tilt individually as required to maintain the log gripping members in engagement with the log throughout substantially the whole of their lineal traverses. To make the tracks self-centering as well, so that the log will be maintained in axial alignment with the barking mechanism, there are provided operative connections between the tracks or more particularly their associated mounting members to that as the radial spacing of a particular track changes, an equal change will be caused to take place in the radial spacing of the other tracks.

The novel features of the invention, together with further objects and advantages thereof, will become more readily apparent when considered in connection with the accompanying drawings in which:

Fig. 1 is a view in elevation of a conventional debarking machine with portions broken away to show the apparatus of the present invention;

Fig. 2 is a sectional view taken on line 2—2 of Fig. 1 illustrating in detail one of the feeding mechanisms of the apparatus according to the present invention;

Fig. 3 is a sectional view taken on line 3—3 of Fig. 2; and

Figs. 4 and 5 are sectional views taken on lines 4—4 and 5—5 respectively of Fig. 3.

Referring first to Fig. 1 wherein so much of a conventional barking machine is shown as is necessary for a clear understanding of the present invention, it will be observed that the machine includes frame members 10 and 11, the former supporting a drive motor 12 for the drum 13, and the latter supporting a motor 14 and gear box 15 to drive the feeding mechanisms. To rotate the drum at the most efficient speed for barking, the drum is driven through a jack shaft 16 mounting a pair of pulleys 17 and 18 which are individually coupled to suitable pulleys on the motor shaft and on the drum by means of V-belts 19 and 20, respectively. To drive the feed mechanisms, on the other hand, speed reducing gear box 15 has its input shaft coupled to motor 14, and its output shaft coupled to one of the shafts 21 associated with the feeding mechanisms of the present invention by means of a V-belt 22. There are two other shafts 23 and 24 associated with the feeding mechanisms which are similar to shaft 21, and which are coupled thereto by means of a timing belt 25. A conventional infeed conveyor 26, as is commonly used to present logs one after another to a barking machine, is shown in outline at the infeed end of the machine.

Since the two feeding mechanisms which comprise the apparatus of the present invention are substantially the same and are driven through shafts 21, 23 and 24 which are common to both, the invention will be described at length with reference only to the input feeding mechanism which is shown in considerably more detail in Fig. 2.

With reference now to Fig. 2 and its related sectional views of Figs. 3 and 4, it will be observed that this feeding mechanism includes three articulated tracks 27, 28 and 29, disposed symmetrically about the axis of the drum and radially spaced therefrom by equal amounts. Each articulate section of track has a pair of transversely spaced lugs, such as lugs 30, which project inwardly from the track section and through which there is passed a pin 31. Projecting outwardly from each section of the track, is a log gripping member 32. Log gripping member 32 is in essence constituted by a bar having a series of transversely spaced notches therein for engagement with a log

33 during a lineal traverse of the track which extends normally adjacent and parallel to the axis of the drum.

To drive each of the tracks such as track 27 of Fig. 3, there are provided a pair of axially spaced sprockets 34 and 35 whose teeth are arranged to mesh with the pins 31 when the track is passed around the gears. Sprocket 34 is adapted to be rotatably mounted on a stub shaft 36 formed at the end of a pivot arm 37, and to this end a bushing 38 is provided in the hub of the sprocket for rotating contact with the shaft. Sprocket 34 is maintained in position axially by a shoulder portion 39 on the shaft 36 and a cap 40 fastened to the end of the shaft to hold the hub against the shoulder. With reference now to sprocket 35, it will be observed that the same is keyed to a driving shaft 41 which extends generally longitudinally and interiorly of a second pivot arm 42 which is axially spaced from the pivot arm 37. To rotatably support shaft 41, there is a ball bearing 43 in a cylindrical bore at one end of pivot arm 42 and a ball bearing 44 mounted in similar fashion at the opposite end of the arm. Bearings 43 and 44 are held in place by caps 45 and 46, respectively, the former in combination with a nut 47 which is threaded onto the end of the shaft towards the left of Fig. 3 serving to fix the position of the shaft axially.

Arms 37 and 42 in turn are pivotally supported by three pillow blocks 48, 49 and 50 disposed in spaced axial alignment with one another, and for this purpose, there are joined to the respective arms hollow tubes 51 and 52, respectively, which mount bearing sleeves 53, 54 and 55, 56 for pivotal contact with the inner walls of the pillow blocks. As best shown in Fig. 3, tube 51 extends between pillow blocks 48 and 49, and tube 52 extends between pillow blocks 49 and 50, the adjacent ends of the tubes lying relatively close to one another in the central region of pillow block 49. To fix the axial position of the tubes with respect to the pillow blocks to the extent that the sprockets 34 and 35 will be held apart a fixed amount and the track 27 maintained under proper tension, one end of the pillow block 48 is provided with an annular recess for a thrust bearing 57 which is held in place by a nut 58 threaded onto the end of the tube 51. In contact with the end of pillow block 49 remote from the pillow block 48, there is another thrust bearing 59 carried in an annular recess in tube 52 whose diameter at this point is somewhat enlarged, as shown. Pillow blocks 48-50 are in turn bolted to a fixed frame member 60 associated with the feeding mechanism.

Extending axially of the assembly of the tubes and pillow blocks thus formed, there is seen the shaft 21 which is journaled in suitable bearings 61 and 62. A pair of axially spaced cartridges 63 and 64 are provided to support the respective bearings 61 and 62 radially and a cap 65, pressed into the outer end of cartridge 64 serves in combination with a flange portion 66 on cartridge 63 to restrain the shaft axially. As shown, the shaft 21 is formed in sections which are intercoupled by means of universal joints 67 and 68, thereby insuring free rotation of the shaft irrespective of any slight misalignment of bearings 61 and 62 with respect to the corresponding bearings of track 84 of the output feeding mechanism.

With particular reference now to Figs. 2 and 3, it will be observed that sprocket 35, one of the driven sprockets, is driven through a worm 69 keyed to shaft 21 and a wheel 70 keyed to shaft 41. By virtue of this mode of coupling, pivotal movement of the track is permitted to take place without affecting its driven relation to shaft 21. To bias the tracks so that their log gripping members will be urged into engagement with a log, there are provided a number of pneumatic resilient devices 71, one for each pivot arm. Each pivot arm, such as arm 37, for example, has a flat thereon against which its associated resilient device 71 bears, the latter being held by fixed frame member 60.

There is joined to each tube member, such as, for ex-

ample, tube member 51, a lever 72 having a pair of arm portions 72' and 72" whose respective edge surfaces cradle a pair of connecting rods 73 and 74. Drilled lug portions through which the connecting rods 73 and 74 are passed are provided at the tips of the respective arm portions, one end of each of the rods being threaded and having nuts 75 and 76 thereon to connect the rods to the lever. The opposite ends of the rods are likewise threaded for connection with the adjacent levers and, in this way, the three arms in each angularly spaced group are adapted to pivot in concert, by equal amounts, to maintain the logs in axial alignment with the drum. There is also provided a rubber pad 77 on each arm 72 for contact with frame member 60 to limit the pivotal movement of the arm in a clockwise direction (Fig. 2) and thereby prevent the tracks from closing to the extent that they come in contact with one another.

Between each pair of arms, such as arms 37 and 42, are means to limit their pivotal movement relative to one another. For this purpose, as best shown in Fig. 5, there is clamped onto arm 42 a bar member 81 which extends in the general direction of arm 37, and there is joined to arm 37 a cooperating fork member 82. The fork like projections of member 82 respectively overlie and underlie portions of the surfaces of member 81 where there are rubber bumpers 83 to cushion the force exerted by one member on the other when the tendency is for one of the arms 37 and 42 to pivot relative to the other more than a predetermined amount as determined by the spacing between the bumpers and the member 82.

In operation, shafts 21, 23 and 24 are driven at a relatively low speed through the gear box and pulleys, each shaft serving to drive two track assemblies associated with the feeding mechanisms adjacent opposite ends of the drum 13. Thus, shaft 21, for example, serves to drive both tracks 27 and 84, the former being driven through worm 69 and wheel 70 which is rigidly mounted on shaft 41. Shaft 41 in turn drives sprocket 35, the driving gear for the track, and through the track the idler sprocket 34 is driven. As is apparent from Fig. 2, the two other tracks of each feeding mechanism are driven in like manner by shafts 23 and 24.

Each log to be barked is presented to the input feeding mechanism from infeed conveyor 26 and by virtue of the pivotal mounting of the tracks and the biasing thereof by the pneumatic resilient devices 71, the tracks open or close when the log is admitted if its diameter differs from the diameter of the preceding log. In this way, the teeth of the log gripping members are caused firmly to engage the log during the respective lineal traverses of the tracks which normally extend parallel to the axis of the drum. The operative connection between the tracks as is afforded by levers 72 and the connecting rods therebetween insures that the tracks will open and close in concert by equal amounts so that the log will be maintained in axial alignment with the drum. During the transition between the trailing end of one log and the leading end of the next succeeding log, the operation of the tracks is aided in a considerable measure by the ability of the tracks to tilt. Such tilting movement results from the relatively different angular positions which will be assumed by the arms associated with each track when the diameters of successive logs are different. The same is true when surface irregularities occur in a single log whereby the log gripping members are maintained in firm engagement with the log throughout substantially the whole of the lineal traverses of the tracks.

Although the novel apparatus of the present invention has been described in connection with the preferred embodiment herein described, it will be apparent to those skilled in the art that this embodiment is susceptible of various modifications that are within the spirit and scope of the invention. Therefore, the invention should not be deemed to be limited to this embodiment in all de-

tails, but should be deemed to be limited only by the scope of the appended claims.

What is claimed is:

1. Apparatus for axially feeding a log through a barking mechanism, said apparatus comprising a feeding mechanism adjacent an end of the barking mechanism, said feeding mechanism including a group of at least three angularly spaced endless tracks disposed symmetrically about the axis of the barking mechanism and having respective lineal traverses extending normally parallel and adjacent to said axis, the individual tracks being provided with a plurality of log gripping members extending generally transversely thereof to engage a log during said lineal traverses; a pair of axially spaced sprockets to drive each of the tracks and thereby advance the log axially; a pair of shafts mounting said pair of sprockets, respectively, at least one of said shafts being adapted to drive the sprocket mounted thereon; a pair of pivot arms mounting said shafts, respectively, said pivot arms having inner portions carrying said tracks and outer portions extending radially outwardly of the pivot points of said arms, fixed support means extending generally parallel to the axis of the barking mechanism for individual pivotal connection with said pivot arms, biasing means acting on the individual support arms to urge the tracks towards the log; means to limit the extent of the relative pivotal movement of the sprockets; and connecting means including cable means extending between angularly adjacent outer portions of the pivot arms to equalize the pivotal movement thereof and thereby maintain the log in axial alignment with the braking mechanism.

2. Apparatus for axially feeding a log through a barking mechanism, said apparatus comprising a feeding mechanism adjacent an end of the barking mechanism, said feeding mechanism including a group of three angularly spaced endless tracks disposed symmetrically about the axis of the barking mechanism and having respective lineal traverses extending normally parallel and adjacent to said axis, the individual tracks being provided with a plurality of log gripping members extending generally transversely thereof to engage a log during said lineal traverses; a pair of axially spaced sprockets to drive each of the tracks and thereby advance a log axially, a pair of shafts mounting said pair of sprockets, respectively, a pair of pivot arms mounting said shafts, respectively, said pivot arms having inner portions carrying said tracks and outer portions extending radially outwardly of the pivot point of said arms, means to drive at least one of said shafts; including a drive shaft geared to the driven shaft; fixed hollow cylindrical support means disposed concentrically about said drive shaft and being adapted to rotatably mount the same; means to join pivotally said pivot arms to said support means permitting said arms to pivot independently of one another; pneumatic compression spring biasing means acting on the individual pivot arms to urge the tracks toward the log; means to limit the extent of the relative pivotal movement of the arms; and connecting means including cable means extending between angularly adjacent outer portions of the pivot arms to equalize the pivotal movement of the arms and thereby maintain the log in axial alignment with the barking mechanism.

3. Apparatus for axially feeding a log through a barking mechanism including three substantially equi-length arms, pivot means mounting said arms generally centrally thereof for swinging movement each about an axis parallel to the line of feed to provide inner and outer portions thereof, means supporting the pivot means at points on the corners of an imaginary equi-lateral triangle having a center coinciding with the center of the line of

70

feed, log gripping means mounted on the inner portion of each arm to engage logs to support and guide them substantially coincident with the center of the triangle, pneumatic compression spring biasing means resiliently urging the arms and thus the log gripping means toward the center of the line of feed, means to limit the extent of relative pivotal movement of said arms moving said log gripping means in a direction toward the center of said line of feed, and connecting means including cable means extending between the outer portions of adjacent arms radially outwardly of said pivot means so that any swinging movement of one arm about its pivot means is transmitted to the other two arms in substantially the same degree.

15 4. Apparatus for axially feeding a log through a barking mechanism including three substantially equi-length arms, pivot means mounting said arms generally centrally thereof for swinging movement each about an axis parallel to the line of feed to provide inner and outer portions thereof, means supporting the pivot means at points on the corners of an imaginary equilateral triangle having a center coinciding with the center of the line of feed, log gripping means mounted on the inner portion of each arm to engage logs to support and guide them substantially coincident with the center of the triangle, biasing means resiliently urging the arms and thus the log gripping means toward the center of the line of feed, means to limit the extent of relative pivotal movement of said arms moving said log gripping means in a direction toward the center of said line of feed, and connecting means including cable means extending between the outer portions of adjacent arms radially outwardly of said pivot means so that any swinging movement of one arm about its pivot means is transmitted to the other two arms in substantially the same degree.

20 5. Apparatus for axially feeding a log through a barking mechanism including three substantially equi-length arms, pivot means mounting said arms each for swinging movement about an axis parallel to the line of feed, means supporting the pivot means at points on the corners of an imaginary equilateral triangle having a center coinciding with the center of the line of feed, log gripping means mounted on the inner portion of each arm to engage logs to support and guide them substantially coincident with the center of the triangle, pneumatic compression spring biasing means resiliently urging the arms and thus the log gripping means toward the center of the line of feed, means to limit the extent of relative pivotal movement of said arms moving said log gripping means in a direction toward the center of said line of feed, and mechanical connecting means extending between adjacent arms radially outwardly of said pivot means so that any swinging movement of one arm about its pivot means is transmitted to the other two arms in substantially the same degree.
